UNITED STATES PATENT OFFICE.

EDGAR E. GREVE, OF BELLEVUE, PENNSYLVANIA.

ROTARY DRILLING MACHINE.

Application filed January 23, 1926. Serial No. 83,256.

My invention relates to improvements in rotary drilling machines and more particularly to new and improved driving members or means employed in machines of this character between the rotary table or gear ring and the drilling string for transmitting power from the machine to the rotatable drill string.

In machines of the type of the present invention, a drive member or spider is disposed in the central opening of the rotary, said spider being designed to receive drive bushings and when desired, pipe slips. This spider or drive member is rotatable with the rotary table or gear ring and through the bushings connects the grief stem of a string of drilling casing to the rotary.

Among the objects of my invention are, to provide new and improved driving members of the character specified having interlocking elements designed to lock said members together to permit a simultaneous rotary movement thereof and prevent a relative vertical movement; to provide driving members adapted to be nested and of such a character as to provide frictional contact between tapering contacting surfaces on the said members; and to provide a simple and efficient construction including two members having cooperating locking means of a construction permitting the members to be readily engaged and disengaged.

In the accompanying drawings, which illustrate an application of my invention:

Figure 1 is a top plan view of the spider member included in my invention;

Figure 2, a similar view of a drive bushing member;

Figure 3, a vertical sectional view, the section being taken on line III—III of Figure 1;

Figure 4, a side elevational view of the drive bushing member; and

Figure 5, a part elevational and a part sectional view of a rotary drilling machine embodying my invention:

In Figure 5 of the drawings I have shown my invention embodied in a rotary drilling machine and I have shown it in connection with a grief stem A. The rotary may be of any preferred construction; as illustrated it includes a rotatable table 5 having a gear ring 6, the latter being coupled with a gear wheel 7 carried on the end of a drive shaft 8. 55 9 designates a drive member of the rotary,

this member being adapted to receive the spider or bushing carrying member of the rotary.

My invention includes a spider or drive bushing carrier member 10. This member as 60 shown and as preferred comprises a body having a tapering centrally disposed bore 11, said bore towards its upper end being slightly enlarged to form an annular ledge or flange 12, a slightly tapering portion 13, 65 and a still further enlarged portion 14.

Formed on and projecting inwardly from the wall 15 of the enlarged portion 14 of the bore, I provide a plurality of contact members or dogs 16, each member 16 being formed 70 with a slightly inclined face a, the latter having a slight tapered portion b.

In addition to the member 10 the present invention includes a drive bushing member 17 designed to fit within the tapered bore of 75 the carrier 10 with the walls of said members frictionally engaging one another. The bushing member is formed as shown, from a single piece of suitable metal and has a central non-circular bore 18 adapted to receive 80 a portion of the non-circular grief stem A. Formed on or secured to the outer surface of the tapered body of the hollow bushing, are a number of projecting contacting members 19. Members 19 are designed to engage 85 the dogs or members 16 when the bushing is positioned within the member 10. Each member 19 is formed with an inclined and tapered face adapted to engage the face of one of the members 16 of the bushing receiving 90 member 10. c designates the inclined contact face corresponding with face a of member 16 and d the tapered portion.

In assembling the members, member 17 is first entered in the bore of member 10 and 95 then turned counter-clockwise, causing the contacting member 19 of the bushing to pass under and make engagement with the respective members or dogs 16 with the inclined and tapered faces of the members of the bushing in contact with the corresponding faces of the members of the spider or bushing carrier.

To prevent the disengagement of the interlocking members 16 and 19 in the event that 105 the rotation of the rotary be changed from a clockwise rotation to a counter-clockwise rotation, I provide locking pins 20.

It will be understood that in the normal operation, the driving members are driven 110

in a clockwise direction and that the members 16 of the bushing carrier are forced up on the members 19.

These cooperating locking means not only provide a simple and efficient construction for locking the two members 10 and 17 together, but in addition thereto, function to prevent a relative vertical movement of the said members.

10 What I claim is:—

The combination with a rotary drilling machine, of a spider having a tapering bore, an enlarged opening above the tapering bore and a wedging locking member disposed in 15 the enlarged portion, and a drive bushing having a tapering body and a wedging lock-

ing member disposed on the outside of the upper portion of the bushing, said bushing entered in the bore of the spider with the locking member thereof in the enlarged portion of the spider and engaging the locking member of the spider, a key insertible between the spider and bushing when the same are in operative position to lock them against relative rotative movement, the construction 20 providing a double wedge action between the spider and bushing, and the locking member of the bushing serving as a drive means for the spider.

25 In testimony whereof I affix my signature.

EDGAR E. GREVE.
